United States Patent

Des. 240,294
Patented June 15, 1976

240,294

LIFT TRUCK BODY

Donald J. De Priester and Darrell C. Fuller, Niles, Mich.,
assignors to Clark Equipment Company

Filed Nov. 27, 1974, Ser. No. 527,787

Term of patent 14 years

Int. Cl. D12—05

U.S. Cl. D12—61

FIG. 1

FIG. 2

FIG. 3

FIG. 4

FIG. 5

FIG. 1 is a right side perspective view of a lift truck body, showing our new design;

FIG. 2 is a right rear quarter perspective view;

FIG. 3 is a left front quarter perspective view;

FIG. 4 is a front perspective view; and

FIG. 5 is a rear perspective view thereof.

Portions shown in broken lines are included for illustrative purposes only.

We claim:

The ornamental design for a lift truck body, as shown and described.
